H. C. HETTELSATER

SUCTION SWEeper

Filed Feb. 3, 1923

Inventor
Henry C. Hettelsater
By *N.J. DiMarsce*,
Attorney

UNITED STATES PATENT OFFICE.

HENRY C. HETTELSATER, OF CANTON, OHIO, ASSIGNOR TO THE HOOVER COMPANY, A CORPORATION OF OHIO.

SUCTION SWEEPER.

Application filed February 3, 1923. Serial No. 616,858.

To all whom it may concern:

Be it known that I, HENRY C. HETTELSATER, a citizen of the United States, and a resident of Canton, in the county of Stark and State of Ohio, have invented new and useful Improvements in Suction Sweepers, of which the following is a full, clear, and exact description.

This invention relates particularly to means for adjusting the nozzle of a suction sweeper by raising and lowering the same with relation to the surface to be operated upon.

It is common practice in the manufacture of sweepers to provide at the front part of the machine a pair of axially arranged supporting rollers or wheels adjacent the nozzle, and to provide one or more supporting wheels positioned toward the rear of the machine.

To raise or lower the nozzle with relation to the carpet or object to be cleaned, means are embodied to raise or lower the axis of either the front or rear wheels.

An object of this invention is to devise means of improved construction for adjusting the axis of one of the supports of the device and which shall be positive in its operation and simple in its construction.

Another object is to make the adjusting device quickly and easily operable to secure the desired adjustment, and to so construct the same that it will be very securely locked in the adjusted position to maintain the nozzle in any position given it with relation to the surface to be cleaned.

The above and other objects will become apparent from the following description, taken in connection with the accompanying drawings in the different figures of which the same reference numerals indicate like parts.

In the drawings:

Figure 1 is a side elevation of a suction sweeper showing the application of my invention,

Figure 2 is substantially an elevation of the adjusting mechanism viewed from the front of the machine, the U-shaped supporting member being shown in section,

Figure 3 is a plan view of the U-shaped supporting member,

Figure 4 is a side elevation of the member shown in Fig. 3,

Figure 5 is an edge elevation of the adjusting strap, and

Figure 6 is a face elevation of Fig. 5.

Fig. 7 is a rear elevation of the machine with detail omitted.

Designating the parts by reference characters, 10 indicates the motor-housing and 11 the fan-chamber, 12 the intake nozzle, 13 the discharge-mouth.

The above elements are essential parts of practically all suction cleaners manufactured. The fan-chamber 11, intake-nozzle 12, and discharge-nozzle 13 are usually cast as an integral unit or so connected together as to form a rigid frame which is supported adjacent the intake nozzle by separated wheels 14 mounted on an axle member 15 suitably connected to the cleaner frame.

Rearwardly of the wheels 14 and preferably positioned to run between the path of the wheels 14 are a pair of separated wheels 16. To raise and lower the intake nozzle with relation to the surface to be operated upon, means are provided for vertically adjusting the axis of the rear wheels 16.

My invention is concerned with a novel mechanism for raising and lowering the rear portion of the frame of a cleaner and with means for locking the adjusting mechanism securely in adjusted position.

A particular structure for accomplishing the objects of my invention will now be described.

The rear portion of the frame of a cleaner is supported on wheels 16 which are secured beneath the discharge mouth 13 by means of a bracket 17 which is suitably secured to the underside of the discharge mouth by means, not shown. The lower end of the bracket 17 carries a pivot 18 on which are mounted links 19 carrying at the other end thereof an axle 20 on which the rear wheels 16 are journalled. Secured to one end of axle 20 is the adjusting strap 21 which is a substantially-flat sheet-metal strap member having one end turned at right angles as 22. The bent end 22 of the adjusting strap member 21 is provided with a slot designated at 23, the purpose of which will be described and become apparent as the

specification proceeds. The longer, substantially-straight part of the adjusting-strap 21 is provided with a longitudinal slot 24 and has provided on its face adjustment indicating numerals indicated as a whole by number 26. The lower end of the strap is provided with a circular opening 27.

For the purpose of supporting the adjusting mechanism and for securing the same to the frame of the cleaner, there is provided a substantially U-shaped strap member 28 having one leg thereof 29, formed of a greater length than the other one 30. The end of the leg 29 is bent at right angles and is provided with a hole designated 31, the purpose of which is to receive a bolt for securing the U-shaped member 28 to the frame of the cleaner. The other leg 30 of this member has the end portion thereof bent at an acute angle and is provided with an opening 32 whereby this end of the support member may be secured to the frame of the cleaner by means of a rivet or otherwise. The leg 29 of the U-shaped piece is provided with a relatively large aperture 32^a and the leg 30 with a screw-threaded aperture 33, the purposes of which will become apparent as the description proceeds.

There is further provided a stamped member 34 provided with two legs 35 and 36 directed at right angles to one another. Leg 35 of this member is provided with a screw-threaded aperture 37 and leg 36 is provided with an aperture 38. The remaining portions of the structure comprise two screws, one 39 having preferably a quick-acting thread, and provided near the upper end with a recess 40 which receives the slotted end 23 and the strap 21. The other screw comprises a short threaded member 41 provided with a head 42 and a flange-like portion 43.

For the adjustment of the nozzle of the cleaner, the members mentioned are assembled in the following manner. U-shaped member 23 is attached at 31, 32, to the main frame of the cleaner. Member 21 is inserted between the legs of the U-shaped member and member 34 is also inserted between the legs of the U-shaped member to the rear of member 21. The screw 39 is entered slightly into screw-threaded aperture 37 and the U-shaped recess 23 of member 21 is seated in the necked or recessed portion 40 of screw 39. Screw 41 with wing-head 42 is then inserted through aperture 32^a in the U-shaped member, slot 24 in the adjusting strap member, aperture 38 in the member 34, and the end threaded into screw-threaded aperture 33 in the rear leg 30 of the U-shaped member. The adjusting strap is then positioned so that the aperture 27 in the lower end fits on the end of axle 20 and is secured thereon by spring-ring, spring-washer, cotter, or other similar securing means.

To adjust the nozzle of the cleaner, wing head 42 is loosened and screw 39 turned either clockwise or counterclockwise depending upon whether it is desired that the adjustment should be lower or higher. When the proper adjustment has been obtained, wing head 42 is tightened, clamping adjusting member in position. The change in angular position of the strap 21 is taken care of when adjustment is being made due to the fact that when wing screw 41 is loosened, the angle member 34 is not held securely in position but may also have angular movement; thus as the strap 21 pivots about the screw-threaded portion of wing screw 41, it takes care of the effect of the change in angularity of strap 21 by pivoting about its supporting member 41.

It will be seen that I have provided a very simple yet easily operable means whereby the nozzle of a suction sweeper may be adjusted by an adjustment of the rear wheels thereof and one which when the adjustment is made is securely locked in such adjusted position.

I claim:

1. In a suction cleaner, a main body casting, front and rear supports therefor, the rear support being mounted on a member pivotally mounted on the body casting, means for adjusting the rear support relatively to the main casting comprising a pivot on the main casting, a strap pivotally connected to the rear support and slidably and pivotally mounted on the pivot, a pivoted member mounted on the pivot, and an adjusting member connecting the strap and pivoted member.

2. The combination with a suction cleaner, having a nozzle of means for adjusting the nozzle height comprising a pivoted support member, an adjusting strap secured thereto, a second pivotally mounted member, adjusting means connecting said adjusting strap and said second pivotally mounted member and separate means for securing said adjusting strap and said second pivotally mounted means in adjusted position.

3. In a suction cleaner having a nozzle, means for varying the height of the nozzle comprising a pivot, a support pivotally mounted thereon, a second pivot comprising a clamping screw, an adjusting strap secured to the support and pivoted on the second pivot, an angle member mounted on said second pivot, an adjusting screw mounted in the adjusting strap and screw threaded connecting with the angle member and means associated with said clamping screw to clamp the adjusting strap and angle member at any particular adjusted position.

4. In a suction cleaner comprising a rigid frame having a forwardly extending suction mouth, forward support means mount-

ed adjacent said suction mouth and rear support means mounted upon a movable axle pivotally mounted in relation to said frame, a link comprising the member connecting the axle to the frame, an adjusting device comprising a bracket secured to said frame, two members pivotally mounted on said bracket, one of said members being capable of sliding relative thereto and pivotally secured to said movable axle, means ¹⁰ co-acting with said two members to produce a relative motion between them and means co-acting with said bracket to lock said sliding member in any desired position.

WILLIAM D. HAMERSTADT.

ed adjacent said suction mouth and rear support means mounted upon a movable axle pivotally mounted in relation to said frame, a link comprising the member connecting the axle to the frame, an adjusting device comprising a bracket secured to said frame, two members pivotally mounted on said bracket, one of said members being capable of sliding relative thereto and pivotally secured to said movable axle, means 10 co-acting with said two members to produce a relative motion between them and means co-acting with said bracket to lock said sliding member in any desired position.

WILLIAM D. HAMERSTADT.

CERTIFICATE OF CORRECTION.

Patent No. 1,574,970.

March 2, 1926.

HENRY C. HETTELSATER.

It is hereby certified that the signature of the patentee at the end of the specification in the above numbered patent was erroneously printed as William D. Hamerstadt whereas said name should have been printed as Henry C. Hettelsater; and that the said Letters Patent should be read with this correction therein that the same may conform to the record of the case in the Patent Office.

Signed and sealed this 4th day of October, A. D. 1932.
